A. Smith

UNITED STATES PATENT OFFICE.

ARNOLD WILLMER, OF HANOVER, PRUSSIA, GERMANY, ASSIGNOR TO THE
KORTING GAS ENGINE COMPANY, (LIMITED,) OF NEW YORK, N. Y.

APPARATUS FOR PRODUCING INTERMITTENT MOTION.

SPECIFICATION forming part of Letters Patent No. 417,966, dated December 24, 1889.

Application filed March 28, 1889. Serial No. 305,114. (No model.) Patented in France May 14, 1888, No. 196,289, and in Switzerland May 14, 1888, No. 864.

To all whom it may concern:

Be it known that I, ARNOLD WILLMER, a subject of the King of Prussia, residing at Hanover, in the Kingdom of Prussia, Germany, have invented certain new and useful Improvements in Apparatus for Producing Intermittent Motion, (for which I have obtained a patent in France, numbered 196,289, and a patent in Switzerland, No. 864, dated 5 May 14, 1888;) and I do hereby declare the following to be a full, clear, and exact description of the invention, such as will enable others skilled in the art to which it appertains to make and use the same.

15 The object of my invention is to provide a suitable apparatus for the production of intermittent motion from the continuous motion of an eccentric or crank.

20 In the drawings, Figure 1 represents my invention as applied to a gas-engine, some of the parts being shown in section. Fig. 2 represents a side view of the eccentric-rod and connections, partly in section, on line 2 of Fig. 1. Fig. 3 shows the spring-catch in detail and the varying positions of the parts in diagram. Fig. 4 shows in detail a portion of the main part of the eccentric-rod with the revolving piece D in a position different from that shown in Fig. 1.

25 30 I have illustrated my invention as applied to the operation of the exhaust-valve C of a gas-engine. It is desirable and necessary that the exhaust-valve of a gas-engine should not be opened at every revolution of the engine-crank, but that at certain revolutions it should remain closed. The valve C is operated by the spring-controlled lever N and its connections. The striking of the valve C upon its seat may serve as a stop for the motion of the lever N, or there may be a special stop M interposed. The lever N is connected to the sliding part P of the eccentric-rod, as shown in Figs. 1 and 2. This part P may slide in or upon the main part R of the eccentric-rod; so 35 that the lengthwise motion of the said eccentric-rod R need not be transmitted to the lever N. The main part of the eccentric-rod R is operated by the eccentric B on the shaft A, which turns in bearings on the standard 40 S. On the main part R of the eccentric-rod

is mounted a revolving piece D, which has suitable radial recesses X, alternating with projections Y. This revolving piece D is arranged in the path of the sliding part of the eccentric-rod, so that the end of the said part P 55 may either enter one of the recesses X or abut against one of the projections Y, according to the adjustment of the revolving piece D, as is shown in Figs. 1 and 4.

The adjustment of the revolving piece D is 60 controlled by the lever or spring-catch O, Figs. 1 and 3, which, being pivoted on the standard S, is normally pressed against the stop K by the spring L, and has a projection H, which 65 engages the teeth of a sprocket-wheel F, which is rigidly attached to the shaft or axis of the revolving piece D.

The mode of operation of my invention is as follows: The stop M or the connections between the lever N and the valve C are so arranged that when the revolving piece D is in the position shown in Fig. 1 the end of the sliding part P of the eccentric-rod projects into one of the recesses X during the lower half of the stroke and is withdrawn therefrom 70 during the upper half of the stroke of the eccentric-rod. In consequence of this the lever N and valve C remain motionless, while the part P slides idly within the part R of the eccentric-rod. During the upper half of the stroke 75 of the eccentric-rod, however, while the end of the sliding piece P is withdrawn from the recess X and the revolving piece D is therefore left free to turn, the projection H on the spring-controlled lever O engages with the 80 teeth of the sprocket-wheel F, and on account of the lateral motion of rod R, as shown in Fig. 3, causes it and the revolving piece D to make a fraction of a revolution for every stroke of the eccentric-rod. As a result of 85 this, on the next stroke of the eccentric-rod one of the projections Y is in the path of the sliding part P, as shown in Fig. 4, and consequently during the lower half of that stroke the lever N is pushed down and the valve C 90 opened. It will therefore be seen that the motion of the valve C can be varied by varying the construction of the revolving piece D, by varying the diameter and number of teeth 95 in the ratchet-wheel F, by varying the position 100

of the stop K, and consequently the amount of time during which the pin H shall engage the sprocket-wheel F, &c.

It is evident that the eccentric B might be replaced by a crank, that the vibrating lever N might be replaced by a cross-head sliding in guides on the standard S, and that other changes in the details of construction might be made without departing from the spirit of my invention.

Having therefore described my invention, what I claim as new, and desire to protect by Letters Patent, is—

1. In an apparatus for producing intermittent motion, the eccentric-rod made in two parts, so that one part slides upon the other in the direction of the length of the rod, a revolving piece which is mounted on the main part of the eccentric-rod, and which has alternate recesses and projections which may be introduced into the path of the sliding part of the eccentric-rod, together with a spring-catch which engages with the revolving piece during a certain portion of the stroke of the eccentric-rod, and thereby causes the said revolving piece to make a fraction of a revolution for every stroke of the eccentric-rod, all in combination, substantially as described.

2. In an apparatus for producing intermittent motion, the eccentric-rod made in two parts, so that one part slides upon the other in the direction of the length of the rod, a revolving piece which is mounted on the main part of the eccentric-rod, and which has projections and radial recesses between the projections that may respectively oppose or permit the passage of the sliding part of the eccentric-rod, a sprocket-wheel mounted on the

axis of the revolving piece and rigidly connected thereto, and a spring-pressed lever which vibrates in the direction of the stroke of the eccentric-rod, and which has a projecting pin which engages with the sprocket-wheel during a certain portion of the stroke of the eccentric-rod, all in combination, substantially as described.

3. In an apparatus for producing intermittent motion, the following parts in combination: a standard, an eccentric mounted on a shaft supported by said standard, an eccentric-rod made in two parts, so that one part slides on the main part in the direction of the length of the rod, a driven piece connected to the sliding part of the eccentric-rod and spring-pressed against a suitable stop on the standard, a revolving piece which is mounted on the main part of the eccentric-rod and has radial recesses into which the sliding part of the eccentric-rod may enter, together with a spring-catch which is mounted on the standard and engages with the revolving piece during a part of the stroke of the eccentric-rod, whereby the said revolving piece is given a part of a revolution at each stroke of the eccentric-rod, and the sliding part of the eccentric-rod alternately abuts against the revolving piece or enters the recesses therein, so as to move the driven piece during certain revolutions of the eccentric and leave it at rest during others, substantially as described.

In testimony whereof I affix my signature in presence of two witnesses.

ARNOLD WILLMER.
